*John C. Rives
Letters Patent*

The Schedule referred to in these Letters Patent, and making part of the same, containing a description in the words of the said John C. Rives himself of his improvement in the mode of drawing Lotteries.

In the system of drawing Lotteries the tickets are made or numbered by changing as often as it can be done, the numbers, figures, letters, marks, or characters, and on a certain number of decimal points. If numbers are used, compounded of two figures, then each number must be separated by a dot or mark; but if single, simple figures, letters, marks or characters are used, then there is no necessity for such operation. Each and every ticket in a scheme must have on it the same number of numbers, figures, letters, marks, or characters. The number of numbers, figures, letters, marks, or characters, used in making or numbering the tickets multiplied into itself as often as there are decimal points on a ticket, or in other words, as often as there are numbers, figures, letters, or marks, or characters, on a ticket will give the number of Tickets that can be made with that number, figures, letters, marks or characters. For example, if twenty-five numbers, figures, letters, marks or characters, are changed on three decimal points, or in other words, if three of the twenty-five numbers, figures, letters, ... or characters are put on a ticket, the third power of twenty-five (15625) is the number of tickets that can be made. If thirty be changed on three decimal points, the third power of thirty (27000) is the number of Tickets that can be made. If thirty three be changed on three decimal points, the third power of thirty three (35937) is the number of Tickets that can be made. If ten be changed on four decimal points, the fourth power of ten (10,000) is the number of tickets that can be made. If twelve be changed on four decimal points, the fourth power of twelve (20,736) is the number of Tickets that can be made. If eight be changed on four decimal points, the fifth power of eight (32,768) is the number of tickets that can be made. A complete Table made out according to this system will show the following results viz. It will

contain an equal number of each of the numbers, figures, letters, marks, or characters used. They will be equally distributed on all the decimal points. The same numbers, figures, letters, marks, or characters that are found in reading or in reading or in reading from left to right, will also be found in reading or in reading from right to left. The position or relation that any number, figure, letter, marks or characters bears to another will be found to be maintained or occupied by each of the others. To have a Lottery when the Tickets are made or numbered as above described, there must be put into the wheel, such as one as is usually made use of in drawing lotteries, as many of each of the numbers, figures, letters, marks, or characters used in making the tickets as there are decimal points, or numbers, figures, letters, or characters on a ticket. If ten figures, numbers, letters, marks or characters are used in making or numbering the tickets, and four of them are put on each ticket, then four of each must be put into the wheel which together will make forty. For example suppose the ten figures in arithmetic were used, and four put on each ticket. There would be put into the wheel, four 0's, four 1's, four 2's, four 3's, four 4's, four 5's, four 6's, four 7's, four 8's, four 9's. This one example is thought a sufficient explanation as regards putting the numbers figures, letters, marks or characters into the wheel. There must be drawn from the wheel as many numbers, figures, letters, marks, or characters, as there are numbers, figures, letters, marks, or characters on a ticket, which will decide which of the tickets are blanks, and which are prizes, and also what prize or prizes each ticket is entitled to. or if it should be thought best the capital prize might be decided by drawing from the wheel as many numbers, figures, letters, marks or characters, as there are on a ticket for each of them. The secondary prizes by drawing from the wheel

one ballot less than was drawn for each capital prize. The next grade of prizes by drawing from the wheel one ballot less than was drawn to decide the secondary prizes, and so on drawing one ballot less each time, till every grade of prizes were drawn for. In drawing on this system, when a ballot is drawn from the wheel, its number, figure, letter, mark, or character, must be taken, and the ballot again put into the wheel before another one is drawn. This is done to give all those tickets that have two or more numbers, figures, letters, marks, or characters, on them alike an equal chance with those which have each of their numbers, figures, letters, marks, or characters, different. When every grade of prizes in a scheme are drawn for, it is not necessary that the ballots should be returned to the wheel. It is probable that the prizes would be distributed more regularly if the ballots were not returned to the wheel.

After days say not exceeding five after the above specification was drawn to and deposited in the Patent Office, I discovered that it was not necessary to put into the wheel more than one of the figures, letters, or characters, used in making the tickets. Washington 11th Dec: 1826
